SOAP HOLDER

Milton S. Voorhees, 908 Richmond Ave.,
Point Pleasant Beach, N.J.

Filed Sept. 16, 1964, Ser. No. 31,755

Term of patent 3½ years

(Cl. D4—3)

FIG. 1

FIG. 2

FIG. 3

FIG. 4

FIG. 1 is a front elevational view of a soap holder embodying my new design,

FIG. 2 is a bottom plan view thereof;

FIG. 3 is a side plan view, and

FIG. 4 is a rear elevational view thereof, the depending portion at the front being omitted for convenience of illustration only.

The dominant features of my design reside in the portions shown in full lines. The soap cake shown in broken lines in FIG. 3 is included for illustrative purposes only.

I claim:

The ornamental design for a soap holder, as shown and described.
